MANDREL

William A. Kelsey, Minneapolis, Minn.

Application June 24, 1932, Serial No. 619,129

11 Claims. (Cl. 32—59)

The object of my invention is to provide an improved mandrel having a jaw capable of a limited rotation to its clamping position with means whereby the jaw will become automatically locked to clamp a tool in the mandrel at the end of a predetermined rotary movement in either direction, the effect being that a smoothing or polishing disk or other tool supported by the mandrel will become firmly held therein whether the disk or tool is rotated forward or backward.

A further object is to provide a mandrel with relatively fixed and movable jaws and a compensating lock device which will automatically lock the jaws against separation while adapting them for use with rotating disks, saws or other tools of varying thickness.

A further object is to provide a locking means for the tool supporting jaw which will increase the locking pressure on the tool proportionately to the resistance of the work on the polishing or grinding face of the tool, whereby as the tendency of the tool and its supporting jaw to turn increases, the greater will be the pressure to prevent such turning.

A further object is to provide means within control of the user of the mandrel to normally prevent separation of the rotating jaw from the fixed jaw and the release of the tool held between them until the operator moves such means to its release position.

Other objects of the invention will appear from the following detailed description. The invention consists generally in various constructions and combinations, all as hereinafter described and particularly pointed out in the claims.

In the accompanying drawing forming part of this specification,

40 Figure 1 is a view of a mandrel embodying my invention;

Figure 2 is a longitudinal sectional view through the mandrel in its clamping position;

45 Figure 3 is a similar view showing the jaws of the mandrel separated to release a polishing disk or other tool;

Figure 4 is a detail view of the upper portion of the member of the mandrel forming the movable jaw;

50 Figure 5 is a sectional view looking at the underside of the movable jaw;

Figure 6 is a top view of the cup-shaped member, the flange of which forms the fixed jaw of the mandrel;

55 Figure 7 is a vertical sectional view through

this cup-shaped member showing the preferred manner of mounting it on the shank of the mandrel, and also showing the cam surfaces for interlocking engagement with the lugs of the movable jaw;

5 Figure 8 is a sectional view on the line 8—8 of Figure 2;

Figure 9 is a sectional view on the line 9—9 of Figure 3;

10 Figure 10 is a sectional view on the line 10—10 of Figure 3;

Figure 11 is a detail view of one of the locking keys for holding the movable jaw in its clamping position.

15 In the drawing 2 represents the shank of the mandrel having a longitudinal bore 3 therein. A stem 4 is adapted to slide in said bore and has a disk 5 at one end provided on the under-

20 side with a depending flange 6 between which and the fixed jaw of the mandrel the disk or other tool may be clamped. The outer end of the shank has a hub 7 thereon to receive a cup-shaped member 8 provided with an annular wall 9 which terminates in an inwardly projecting flange 10 at the upper edge of the wall, this 25 flange forming the fixed portion of the jaw upon which the tool is seated. The flange 10 has op-

posite arranged notches 11 and between these notches upon opposite sides thereof I prefer to provide depending flange members 12 having 30 cam surfaces 13. Depending studs 14 are pro-

vided on the disk 5 terminating in outwardly projecting lugs 15 having beveled faces 16 which engage the cam surfaces 13 and limit the rotary movement of the movable jaw and the stem 35 thereof. These studs have lower edges 17 which pierce the paper or other fibrous material when a disk of this material is used in the mandrel.

When the parts of the mandrel are assembled the studs and lugs having passed through the 40 tool will pass through the notches 11 and enter the cup-shaped member 8 a sufficient distance to allow the tool to be clamped between the fixed and movable member. The movable jaw 5 may then be rotated in either direction until the faces 45

16 of the studs 15 engage the cam surfaces 13 and thereupon the jaw will be locked in its clamped position and the polishing or smoothing disk or other tool will be firmly held. Usu-

50 ally in applying a tool of this kind to the work there will be a tendency to rotate it and the clamping jaw and when this takes place the lugs 15 will slide on the cam surfaces 13 and gradually tighten the grip of the jaws and the double arrangement of these cam surfaces and the cor-

- responding faces of the lugs will produce this clamping effect regardless of which direction the polishing disk, saw, or other tool is rotated.
- During the rotation of the movable jaw it would be possible for an accidental separation to be effected of one jaw from the other at the point where the lugs 15 are in register with the notches 11 in changing the direction of the rotation of the tool, and for the purpose of preventing this possible separation and positively controlling the release of the tool and adapting the mandrel for tools of different thicknesses, I have provided an automatic locking means for the stem 4 which I will now describe in detail.
- The shank 2 has an enlarged portion 18 provided with a series of longitudinal slots 19 arranged at intervals and extending lengthwise of the shank and communicating with the central bore 3. The stem 4 is provided with an inclined surface 20 which when the parts of the mandrel are assembled will be opposite the slots 19. A collar 21 is provided on the shank encircling the lower portion of the slots 19 and is provided with an inner downwardly flaring annular surface 22 that is opposite the surface 20 and parallel substantially therewith. A series of keys 23 fit within the slots 19 and have wedge-shaped heads 24 at their lower ends for contact with the surfaces 20 and 22. The upper ends of these keys have outwardly projecting lugs 25 and ears 25' which slide on the walls of the slots and prevent inward movement of the keys and their displacement in the slots. A coil spring 26 is seated on the collar 21 and a flat ring 27 rests on this spring and forms a support for the lugs 25 and the keys. A sleeve 28 encircles the spring 26 and the locking keys and is slidable on the collar 21 and has an inwardly projecting flange 29 which bears on the lugs 25 of the locking keys. This sleeve is free to slide lengthwise upon the mandrel under pressure of the fingers of the operator, and when it is pushed downwardly and the spring 26 compressed, the wedge-shaped heads 24 of the keys will slide down between the surfaces 20 and 22 and release the stem 4, allowing it to be pulled out of the shank of the mandrel, at which time a disk or other tool may be placed on the fixed jaw, the stem inserted through the central opening in the disk and the lugs on the movable jaw pressed through the disk to their locking position, and when this has been done the operator will release the sleeve 28 and allow it to return to the position shown in Figure 2, where the locking keys will lie in the path of the inclined surface 20 of the stem and positively prevent the stem from being pulled out of the shank.
- The disk or other tool will be held between the jaws of the mandrel and forward or backward rotation of the tool will be permitted, the movable jaw rotating from one locking position to the other and during this change in the direction of rotation of the tool it will be impossible for the movable jaw to become released and separated from the fixed jaw when the studs 14 are in register with the notches 11 as the stem 4 will at that time be securely held by the locking keys, and while rotation of the stem is permitted it will be securely held against outward longitudinal movement.
- Whenever desired, the operator grasping the sleeve 28 may push downwardly thereon, as illustrated in Figure 3, and move the locking keys to their release position, as indicated in this figure, thereby permitting the stem 4 to be pulled outwardly and the movable jaw separated a sufficient distance from the fixed jaw to release the disk or other tool that has been clamped between them.
- The tapered surface on the stem and the corresponding surface of the encircling collar allows the locking device to automatically compensate for varying thicknesses of the tools that may be inserted between the jaws. The operator of the mandrel may at one time desire to clamp a comparatively thin disk and then immediately thereafter have use for a thicker disk, saw or other tool and regardless of the variation in the thickness of the tools the locking device will automatically adapt itself to positively hold the jaws against premature separation, while at the same time freedom of rotation of one jaw with respect to the other is permitted, and during this rotation and when the jaws are at the point where separation is permitted in passing from one cam surface to another, the lock will positively hold the jaws together until such time as it is moved to the release position by the operator.
- With this mandrel, the operator may easily and quickly clamp a paper disk, saw or other tool varying in thickness in place and rotate it forward or backward as may be desired in the operation of the mandrel, and this forward or backward movement may be accomplished without danger of releasing the tool or disengaging the movable jaw from the fixed jaw.
- This invention, while adapted particularly for use as a dental mandrel, may be incorporated in mandrels adapted for other purposes where it is desirable to adapt the device for gripping disks or tools of different thicknesses and where a forward or backward movement of the tool is desirable without affecting the gripping or clamping elements.
- I claim as my invention:
1. A dental mandrel having a fixed jaw provided with a cavity and a flange encircling said cavity provided with oppositely arranged notches, a movable jaw having studs provided with heads to enter said notches and rotate forward or backward in said cavity, the inner walls of said fixed jaw having surfaces cooperating with the surfaces of said heads whereby said movable jaw will become locked when rotated a predetermined distance in either direction, and said heads and studs being adapted to puncture a disk preparatory to clamping it between said jaws.
  2. A dental mandrel comprising a shank having a bore therein, a fixed jaw on said shank, a movable jaw having a stem slidable in said bore, said movable jaw having studs thereon and said fixed jaw having notches to receive said studs, and said studs and the inner walls of said fixed jaw having cooperating surfaces for limiting the rotary movement of said movable jaw in either direction, and simultaneously drawing the jaws together to clamp a tool between them, and said shank having means whereby the premature separation of said movable and fixed jaws is prevented when its studs are in register with said notches during the forward or backward rotation of said movable jaw.
  3. A mandrel comprising a shank having a fixed jaw thereon and provided with a longitudinal bore, a movable jaw having a stem to slide in said bore and provided with an inclined surface, a collar encircling said stem and having an inner corresponding surface, a series of

spring-pressed locking keys slidable in slots provided in the walls of said shank between said collar and stem and having surfaces for normally contacting with the opposing surfaces of said stem and collar to lock said stem against premature outward movement, and a sleeve encircling said keys and shank whereby the operator may move said keys to their release position against the tension of said spring.

10 4. A mandrel comprising a shank having a longitudinal bore therein and provided with a fixed jaw, a movable jaw having a stem to enter said bore and rotate and slide therein, a collar encircling said shank and stem, a series of locking keys interposed between said stem and collar and having surfaces cooperating with surfaces on said stem and collar for normally locking said stem against outward movement while permitting rotating movement thereof, 15 said jaws having cooperating means whereby their clamping surfaces will be drawn together as said stem and movable jaw are rotated, said keys during such movement locking said stem against outward movement, and means whereby the operator may move said keys to their release position and allow the separation of said jaws.

5. A mandrel comprising fixed and movable jaws having a relative rotary movement, means whereby such rotary movement in either direction will draw said jaws together to clamp a tool between them, the degree of pressure on the tool increasing proportionately with the relative rotation of the jaws, said means allowing separation of said jaws at a predetermined point in their rotation and means whereby premature separation of said jaws is prevented.

6. A mandrel comprising a shank provided with a longitudinal bore and having a fixed jaw thereon, a movable jaw having a stem to enter said bore and slideable therein to allow said movable jaw to be adjusted in its locking or releasing position, the stem of said movable jaw having an inclined surface thereon, a collar on said shank encircling said stem and having an inner inclined surface opposite and spaced from the corresponding surface of said stem, locking keys interposed between said stem and collar and having surfaces cooperating with the inclined surfaces of said stem and collar to normally lock said stem and movable jaw in any of their adjusted clamping positions, and means for moving said keys to a release position and allow adjustment of said stem to compensate for varying thicknesses of the tools between said jaws.

7. A device of the class described comprising clamping members driving and driven, means by which one member is rotatably and translatably journaled in the other, means by which the members are coupled as a result of axial trans-

determined rotative angular relation to one another, means by which after coupling, said members are moved to clamping relation as a result of rotative motions in either direction from the coupling position, and means for preventing translative uncoupling of the members but permitting rotation therebetween as a result of reversing rotations of the driving member.

8. A device of the class described comprising clamping members driving and driven, means by which one member is rotatably and translatably journaled in the other, means by which the members are coupled as a result of axial translation and only when the members have a predetermined angular relation to one another, 15 means by which after coupling said members are moved to clamping relation as a result of a predetermined degree of rotative motion in either direction from the coupling position, and means for preventing translative uncoupling of 20 the members.

9. A device of the class described comprising clamping members driving and driven, means by which one member is rotatably and translatably journaled in the other, means by which the members are coupled as a result of axial translation and only when the members have a predetermined angular relation to one another, 25 means by which after coupling said members are moved to clamping relation as a result of rotative motion from the coupling position, and means for preventing translative uncoupling of the members, said coupling means being adapted to traverse openings in a tool which is to be clamped between said members.

10. A mandrel comprising a fixed jaw and a movable jaw, the movable jaw having a pin which is rotatable and translatable in the fixed jaw, means by which rotary movement of the movable jaw, in either direction will draw the same toward the fixed jaw proportionately to a degree of rotation to clamp a tool between the jaws, means on the fixed jaw automatically locking the pin of the movable jaw to prevent separation of the jaws, and means manually movable to move said automatic locking means to unlocking position.

11. A mandrel comprising fixed and movable jaws, the movable jaw having a pin rotatable and translatable in the fixed jaw, said pin having a portion convergently tapering in a direction toward the cooperating point of the jaws, means by which rotative movement of either jaw will draw the jaws together to clamp a tool between them, means operating automatically on the tapering portion of the pin for automatically preventing unlocking withdrawal of said pin, and means manually operable for moving said last mentioned means to permit withdrawal 60 of the pin.

WILLIAM A. KELSEY.
